ABSTRACT

3,5 dichloroaspirin is administered orally or intravenously to render more negative the surface charge of the interior surface of the vascular system and thereby to decrease thrombotic tendency therein. This also increases the streaming potential of the vascular interface and increases Lee White clotting times, thrombin times, and partial thromboplastin times and recalcification times. The overall effect is to decrease thrombotic tendencies and to increase blood flow in the extremities. A method is provided for evaluating 3,5 dichloroaspirin and other such compounds.

EVALUATING PHARMACEUTICAL COMPOUNDS**

FIELD OF INVENTION

This invention relates to pharmaceutical compounds for treating the vascular system and to methods of evaluating pharmaceutical compounds.

BACKGROUND

Various cell systems have been investigated in an attempt to explain specificities in cell recognition, rejection and adhesion (Danielli, J. F. Cell to cell interaction. *J. Physio.* Vol. 98: 109, 1940). Evidence indicates that platelets and erythrocytes have common surface properties that may greatly influence cell-cell interactions (Seaman, G. V. et al. Cell interaction a surface charge phenomena. *Biochem. Biophys.* Vol 117, 1966; Mehrishi, J. N. Phosphate groups on the surface of human blood platelets, *Nature*, Vol. 226, 5244, 1970; Davies, D. F., et al. The electrophoretic mobility of RBC as a measure of the surface activity. *Clin. Sci.*, Vol. 17, 1965). One such property is the negative surface charge of the membrane, which was first described by Abramson in 1928 (Abramson, H. A. Electrophoretic migration of inert particles and blood cells in soils and gels. *Amer. J. of Med. Sci.* Vol. 167, 1928). Intact cells at a physiological pH tend to move toward an anode as can be shown by quantitative electrophoresis measurements. The effect is accounted for by an excess of anionic over cationic groups in the surface layer that determines electrophoretic mobility (Madoff, M. A. et al. Sialic acid of human blood platelets *J. of Clin. Inv.* Vol. 43, No. 5, 1964). Platelets have a true iso-electric point at a pH of 3.5 to 4.5 which indicates that the net negative charge excess is considerable. Upon treatment with neuraminidase, 60 percent of the charge can be removed, apparently due to the removal of sialic acid residues located on the cell surface. Platelets so treated tend to aggregate spontaneously. This then would appear to indicate that electrostatic repulsion is partly responsible for vascular homeostasis (Weiss, L. Biophysical aspects of initial cell interaction with solid surfaces. *Fed. Proc.* Vol. 30, No. 5, Sept.-Oct., 1971; Salzman, E. Role of platelets in blood surface interaction *Fed. Proc.*, Vol. 30; No. 5, Sept. - Oct., 1971).

It is possible to cause platelets as well as other cells to aggregate by the addition of positively charged macromolecules such as polylysine and protamine sulfate (Hampton, J. R., and Mitchell, J. R. A. Modification of the electrokinetic response of blood platelets. *Nature*, 1966; Massini, P. and Luscher, E. On the mechanism of which cell contact induces the release reaction of blood platelets, *Thromb. et Diath.*, Vol. 27, 1972). It has also been shown that positively charged metallic surfaces that exhibit positive potentials vs. NHE in blood/saline are thrombogenic (Sawyer, et al. Relation between Thrombosis on Metal Electrodes and the Position of Metal in the Electromotive Series, *Nature*, Vol. 215, No. 5109, p. 1494, Sept. 30, 1967). Modifications of collagen prostheses to reduce surface negativity promotes thrombus formation in vivo (Sawyer, et al., Critical potential for Thrombus Deposition on Metal Surfaces in Vivo, *Vascular surgical services and the Electrochemistry and Biophysical Labs.* of the Dept. of

Surgery and Surgical Research, State Univ. of N.Y. Downstate Medical Center, Bklyn.).

The above supports the view that electrostatic repulsion per se is in part responsible for platelet noninteraction, at both cell-cell and blood vessel wall-blood cell levels under normal conditions. One explanation of platelet transformation into highly adhesive cells relates to surface charge. Metallic tube implants have demonstrated the relevance of surface potential and thrombogenicity (Sawyer et al., Critical potential for Thrombus Deposition on Metal Surfaces in Vivo supra). Metallic tubes with varying spontaneous potentials in contact with blood were implanted in dogs. Those tubes which possess a homogeneous negative surface potential vs NHE in contact with blood remain patent far longer than did those implants with positive potentials (Sayer et al., Critical potential for Thrombus Deposition on Metal Surfaces in Vivo supra). Likewise, polymer materials with an excess of oriented negative charge residues, (i.e., SO_4^{2-} and COO^-) in contact with blood also support the premise that a homogeneous negative surface potential is one criteria for antithrombogenicity (Sawyer et al., Critical potential for Thrombus Deposition on Metal Surfaces in Vivo).

Potential dependent cell adhesion characteristics were first observed in 1963. The fact has been established, both in vitro and in vivo, that anodic potentials imposed upon a Pt wire produced "cell precipitation." The effects of varying pH and heparin were also established. Results have demonstrated that an acidic pH potentiates cell adhesion, while a basic pH inhibits cell adhesion. A series of experiments produced a semi-quantitative method of evaluating cell adhesion in a highly ordered and controlled environment.

Data is available which correlates potential dependent cell adhesion with the influence of various pharmacological agents on platelet adhesion and thrombus formation on vascular prostheses. Furthermore, various pharmacological agents have been shown to modify thrombus deposition in vivo on metallic prostheses, the injured blood vessel wall and collagen implants (Sawyer et al., Utility of Anticoagulant Drugs in Vascular Thrombosis: Electron Microscopic and Biophysical Study, *Surgery*, St. Louis, Vol. 74, No. 2, PP. 263-275, August, 1973).

SUMMARY OF INVENTION

It is an object of the invention to provide an improved technique for the treatment of vascular systems of warm blooded animals.

It is another object of the invention to provide a new technique for rendering more negative the intimal surface charge of the vascular system.

Yet another object of the invention is to provide an improved technique for decreasing thrombotic tendency in vascular systems.

Still another object of the invention is to provide an improved technique for decreasing the thrombotic tendency in vascular systems as manifested by an increase in the streaming potential of the vascular interface, an increased clotting time, thrombin time, partial thromboplastin time, and recalcification time.

To achieve the above and other objects of the invention, there is provided a method which comprises administering 3,5 dichloroaspirin to a warm blooded animal to render more negative the surface charge on the interior surface of the vascular system and thereby decrease thrombotic tendencies therein. The 3,5 di-

chloroaspirin has the following structure

The 3,5 dichloroaspirin may in accordance with the invention be administered orally. It is preferably administered in an amount in the order of magnitude of about 15 mg./kg. of body weight daily.

The 3,5 dichloroaspirin may also be administered intravenously in accordance with the invention in an amount in the order of magnitude of about 5 mg./kg. of body weight daily.

Other objects, features and advantages of the invention will be found in the detailed description which follows hereinafter.

BRIEF DESCRIPTION OF DRAWING

In the drawing:

FIG. 1 diagrammatically illustrates apparatus for conducting tests in accordance with the invention:

FIGS. 2(a) and 2(b) are charts indicating potential dependent platelet adhesion vs. surface potential in the apparatus of FIG. 1;

FIG. 3 illustrates ADP aggregation levels vs. surface potential aggregation levels in chart form; and

FIGS. 4(a) and (b) illustrate platelet dependent cell adhesion vs. surface potential.

DETAILED DESCRIPTION

As shown in FIG. 1, a Bausch & Lomb movable stage microscope 10 with phase contrast optics and an oil immersion lens was employed. The optics include a phase microscope using an oil immersion lens at 1000 magnification. The microscope is focused on one small area of the platinum electrode in order to observe platelet sticking. A lucite cell or chamber 12 with a volume of 2 ml was constructed so as to allow the easy insertion of a Pt wire electrode 14 and two salt bridges 16 and 18 (agar bridges used as electrolytic conductors).

A Pt electrode with surface properties that are well defined was chosen as the test surface. Of great importance in obtaining accurate results in cleanliness (demonstrably free of blood coagulation factors and other proteins or chemicals which might excite blood clotting), particularly of the lucite cell and the electrodes. To achieve the above, the cell is first rinsed with distilled water and washed with a mild soap solution. The cell is then treated with a solution of 50 percent water and 50 percent methanol in order to denature any proteins or accumulated thrombin. It is finally rinsed with triple distilled water and allowed to dry.

The electrode is cleaned first by immersion in nitric acid for at least 15 minutes and then flamed. It is then inserted into the lucite cell. The cell is filled with a protein-free plasma-like solution, namely Krebs 1 solution (Sawyer et al., *Electrochemical Precipitation of Human Blood Cells and its Possible Relation to Intravascular Thrombosis*, *Proceedings of the National Academy of Sciences*, Vol. 51, No. 3, PP. 428-432, March, 1964). The electrode is further cleaned by passing a cathodic current and degassing the electrode.

The modified Krebs 1 solution is then removed and fresh solution is added for actual experimentation.

Ten ml of human blood are drawn into a sterile syringe and placed into two citrated vacutainers. The blood is centrifuged at 1000 rpm for 20 minutes. This produces a supernatant plasma with a high platelet concentration. 0.5ml of platelet rich plasma (PRP) is then added to the cell already containing 1 ml of the Krebs 1 solution which is then filled (approximately two milliliters) for the purpose of obtaining a series of control values.

In determining the effects of pharmacological agents on the adhesive behavior of platelets, varying amounts of the test drug are added to the above solution. The experiment is run at a pH of 7.35. Tenth normal HCl and NaOH buffer solutions were used for buffering to alter the pH range.

The salt bridges connect with ionic solutions in vessels 20 and 22. The ionic solutions may be, for example, saturated potassium chloride solution or a solution of sodium chloride. A potentiostat 24 was used to control the surface potential of the Pt wire. Current was read by meter 26 and voltage was read by meter 28. First the potential was set at -600 mv vs. NHE and allowed to remain there for 2 minutes. A count of platelets sticking to the electrode was then taken. The potential was then increased in steps of 100 mv and another count taken 2 minutes later. This procedure was repeated until the potential was brought through 0 to +600 mv vs. NHE (normal hydrogen electrode). The initial potential was not set below -600 mv vs. NHE in an effort to avoid the formation of gas bubbles on the electrode.

After each run, the apparatus is cleaned as previously described and another run is made. Upon completion of a series of experiments, the number of adherent platelets are averaged at each potential and a deviation from the mean is tabulated. The experimental results can best be represented by graphs, where the number of platelets adhering to the electrode is plotted against potential of the electrode under varying experimental conditions.

Included among the agents evaluated were (a) three anticoagulants, namely: heparin, aspirin (ASA), and 3,5 dichloroaspirin, (b) coagulants, namely protamine sulfate and chlorpromazine, and (c) a proteolytic enzyme (brinase); code number herein C₂. The drug concentrations used (except for 3,5 dichloroaspirin which was not previously used) were in most cases ten times less than normal, normal and ten times greater than normal with respect to a clinical therapeutic dosage. The term "normal" as used herein means the average concentration normally found in plasma when the drug is administered orally and implies the maximum normal blood level with non toxic effect by whatever route the material is administered.

On the basis of ten independent blood samples, a standard curve (see FIGS. 2(a) and 2(b)) was arrived at for the potential dependent adhesion characteristics of human platelets on Pt wire. Analysis of the control graph shows a peak in the curve at -400 mv. NHE, far below the plateau region which starts at the anodic potential of +400 mv NHE. It is this point in the curve where one observes reversible migration of platelets toward the electrode followed by subsequent primary stage platelet adhesion. This reversible aggregation phenomena also occurs *in vivo* with the blood vessel wall and has been reported in other test systems, evalu-

ating platelet adhesion (Fulher, M. B., et al. Reversible alterations in platelet morphology produced by anticoagulants and cold blood. vol. 9, 602, 1954). One cannot, however, actually say whether the charge on the metal at this potential is comparable to the charge density of an equal area of the blood vessel wall.

At a potential near the point of zero charge (PZC) of the Pt electrode what appeared to be first stage viscous metamorphosis (agglutination) was observed. This same observation was made in previously reported research, utilizing a mercury drop electrode. In an attempt to establish whether the point of zero charge and any anodic potential thereafter was inducing the platelet release reaction, a series of experiments was conducted using ADP (adenosine diphosphate) results in aggregation curves utilizing known optical techniques. Stated otherwise, in order to determine if platelets or blood cell precipitation was related to point of zero charge, a series of experiments was carried out measuring the precipitation potential of blood cells on electrodes constructed of different metals. The available evidence indicates that the deposition of cells on the electrodes always occurred at approximately the same potential with respect to the normal hydrogen electrode rather than being related to the point of zero charge of the materials in question.

A series of experiments was carried out matching the effects of ADP and the anodic electrode on pertinent aggregation comparing increasingly anodic potentials to the two increasing concentrations of ADP. Thus platelet aggregation decreased turbidity — at various concentrations of ADP in the cell was compared with anodic potential to produce the same degree of aggregation, that is, decreased turbidity.

Following this, samples of PRP (platelet rich plasma) which had been exposed to various anodic potentials for a period of 3 minutes were measured for optical density changes compared with no current control (FIG. 3). By inference, comparing the slope of the control curve, produced by varying concentrations of ADP with the curve produced by anodic potentials, the possible correlation between the anodic potentials, inducing platelet release reaction, through the release of endogeneous ADP, and ADP addition to the cell can be compared.

As one approaches the anodic region of the control curve there is a rapid increase in the number of cells adhering to the electrode. Visual observations indicate that second stage platelet adhesion is occurring at approximately +400 mv NHE. Beyond this, the rate of increase in the number of cells adhering to the electrode levels off.

Experiments were conducted comparing heparin, a potent anticoagulant, as a standard and brinase(C₂), a potent proteolytic agent (very capable of lysing proteins). The effect observed with these drugs is plotted in FIG. 2(a). It demonstrates a large reduction in the number of cells adhering to the electrode regardless of the surface potential. The results seem to suggest that heparin is reducing the adhesive behavior of the platelets through an absorption phenomenon. The chemical structure of heparin, which is a repeating polymer of mucopolysaccharide units with an abundance of SO₄⁻ groups represents an ideal compound for increasing the mutual electrostatic repulsive forces between the cells and foreign surface, if absorption takes place. The

results with ASA and with 3,5 dichloroaspirin demonstrate a similar trend. The number of cells adhering to the surface of the electrode fall far below the number adhering in the control situation in the anodic region. At no time was any viscous metamorphosis (agglutination) observed with the addition of ASA. This might be explained by the data of other researchers who suggest that ASA acetylates the platelet membrane and by blocking ADP release, suppresses the secondary wave of platelet aggregation in *in vitro* studies (Stemerman, M. B. Drugs, platelets and vascular injury, Proceedings of the 4th Inter. Hemostasis Conference No. 23, 1972; Mustard, J. F., et al. Modification of platelet function, Ann. of the N.Y. Acad. of Sci., Vol. 201, 1972). The results with C₂, the proteolytic enzyme, are conventional. Some cell lysis was observed. Almost no cell adhesion was seen with varying surface potentials.

The results with protamine sulfate (neutralizing agent for heparin) demonstrate (FIGS. 4(a) and 4(b)) a marked increase in the rate and number of cells adhering to the electrode. What is observed, upon analysis of the curve, is that there is a shift in the potential at which adhesion occurs, i.e., from +400 mv NHE to -200 mv NHE, with an almost linear relationship between potential versus number of cells adhering to the Pt surface. The skeletal proteins of the platelet membrane provide a number of possible sites for bond formation with macromolecular (e.g., COO⁻, NH₂ and SH) groups. The absorption of protamine sulfate onto the platelet membrane through disulfide bridging or due to an acid-base level reaction between the COOH and amine groups can explain the observed behavior.

Chlorpromazine has been reported to block the glucosyltransferase reaction reported to be the basis for platelet adhesion to an organic substrate. The results obtained by the present experiments indicate a conflict. Chlorpromazine seems to enhance the adhesion characteristics of platelets. Here again one is not sure of the mechanism. Chlorpromazine may be involved metabolically, producing an external alteration thus enhancing platelet adhesion in the absence of collagen.

The data presented herein tends to support the promise that mutual electrostatic repulsion between blood platelets and the arterial wall is just one of the forces responsible for homestasis in the blood vascular system (Born, GVR. Current ideas on the mechanism of platelet aggregation, Ann of the N.Y. Acad. of Sci., Vol. 201, 1972). The results indicate that anodic surface potentials enhance platelet adhesion to appropriately charged foreign surfaces *in vitro*. Visual observations link first stage viscous metamorphosis with a point near the point of zero charge of the metal. Maximum platelet adhesion occurs on a Pt wire at a surface potential of +400 mv NHE.

Various anticoagulants such as ASA, 3,5 dichloroaspirin and heparin appear to alter the adhesion characteristics of platelets by a simple adsorption process. Both protamine sulfate and chlorpromazine enhance the adhesive characteristics of platelets. In the latter case the results cannot be explained by a simple adsorption phenomenon, and metabolic involvement must be indicated. This test system seems to be a useful one in evaluating the effects of various pharmacological agents upon platelet adhesion characteristics in association with foreign surfaces.

The structure of 3,5 Dichloroaspirin is

Results using 3,5 dichloroaspirin are shown in the following table (reference being made to Applicant's

Further, it decreases the net negative electroosmotic potential differences of arteries and veins when compared to the control on the four animals tested.

It also increases the net electrophoretic charge of platelets by about 25 to 30 percent. These platelets have been taken from mongrel dogs, 25Kg. body weight using venopuncture. The blood is centrifuged at 1000 rpm for 10 mins. to obtain platelet rich plasma (PRP).

Dichloroaspirin does relatively little to the thrombin

prior U.S. Pat. No. 3,722,504).

Regarding the above electrochemical screen measurements of the canine vessel, tests on streaming potential under control conditions and in comparison with aspirin, electroosmosis of canine artery and veins while using this material, platelet electrophoresis determinations, the effect of 3,5 dichloroaspirin on the charge characteristics of platelets and red cells as indicated, coagulation studies and measurements of the effect of the chemical on rat mesentery electrical thrombosis.

The material given orally 300mg/day (approximately 15mg./kg./day) in dogs does not appear to be toxic to biological systems as indicated by its use in small rats of 100 to 125 grams at an intraperitoneal dose level of 5mgs/Kg/day.

Streaming potential measurements indicate that 3,5 dichloroaspirin increases the net negative charge of arteries and veins. It also serves to maintain the integrity of the net negative charge of the vascular interface under control conditions and injury as indicated under the heading 'Streaming Potential' in the table.

time but increases the partial thromboplastin time (PTT) and the recalcification time (RCT) of blood from the four dogs in which the studies were carried out. Five milligrams per kilogram intraperitoneally one-half hour before the study and 5 mgs/Kg intraperitoneally for each of 5 days before the test prolonged rat mesentery occlusion time from a control level of 48 minutes for a single intraperitoneal dose and 70 minutes for a five day intraperitoneal dose.

Data indicates that 3,5 dichloroaspirin has a dramatic effect on the blood-vascular interface. Rather limited effects which are not entirely explained are seen, by electroosmosis of canine blood vessels, in animals given 60 300 mgs. per day orally and rather marked effects on platelets. The dramatically increased coagulation times and RCT indicated that it has very fundamental effects on the coagulation enzymes.

65 A summary of its physiologic effect as shown by rat mesentery studies demonstrate prolonged rat mesentery electrical thrombosis times and therefore it has profound antithrombotic effects on the intact microcirculation.

There will now be obvious to those skilled in the art many modifications and variations of the subject matter disclosed above. These modifications and variations will not depart from the scope of the invention as defined by the following claims.

I claim:

1. A method for rendering more negative the internal surface of a vascular system in order to decrease thrombotic tendency, said method comprising administering 3,5 dichloroaspirin in the order of magnitude of about 5-15 mg./kg. of body weight daily to a host requiring such treatment, the 3,5 dichloroaspirin having the structure

2. A method as claimed in claim 1 comprising administering the 3,5 dichloroaspirin orally or intraperitoneally to increase the streaming potential of the vascular interface and to increase clotting time, thrombin time, partial thromboplastin time and recalcification time.

3. A method as claimed in claim 2 wherein the 3,5 dichloroaspirin is administered orally in an amount in the order of magnitude of about 15 mg./kg. of body weight daily.

4. A method as claimed in claim 2 wherein the 3,5 dichloroaspirin is administered intraperitoneally in an amount in the order of magnitude of about 5 mg./kg. of body weight daily.
